SPRAY DEVICE

Harold Gold and David M. Straight,
Cleveland, Ohio

Application October 25, 1948, Serial No. 56,322

16 Claims. (Cl. 299—114)

(Granted under the act of March 3, 1883, as
amended April 30, 1928; 370 O. G. 757)

1

This invention relates to improvements in spray devices and more particularly concerns spray devices of a character adapted to produce a finely atomized spray as in supplying fuel into the combustion chamber of a turbo-jet aircraft engine, or the like.

In practical applications, such as in supplying atomized fuel to the combustion chamber of a turbo-jet engine or the like, flow rate of the liquid supply to the spray nozzle may vary over a wide range from zero to a relatively high rate. However, throughout the time of actual liquid atomization, the quality of atomization must remain substantially constant for optimum end results, as in the attainment of a proper combustible mixture of the atomized liquid fuel and air in the combustion chamber of the engine.

The most desirable spray pattern for uses such as that suggested, as well as other uses, comprises a hollow cone shaped spray stream of the atomized liquid. For maximum efficiency in admixture of air with the atomized spray stream of liquid fuel, it is desirable that the spray stream angle be as wide as practicable at any fuel flow rate throughout the range of flow rates provided for in any given installation.

In the attainment of these desirable results, in a simple and efficient manner, the liquid supplied to the spray orifice is caused to assume a high velocity vortex flow immediately upstream from the orifice so that the whirling motion of the liquid persists as the liquid escapes through the orifice and sprays into the space beyond the orifice.

The present invention is especially directed to the means whereby not only is an effective hollow cone shaped spray pattern attained, but the spray cone angle is also maintained substantially constant throughout the operating range of liquid supply flow rates.

It is therefore an important object of the present invention to provide improved means for so controlling the supply of fluid in a spray nozzle assembly that a substantially constant hollow cone shaped atomized spray stream of substantially constant cone angle is attained throughout a relatively wide range of flow rates in operation.

Another object of the invention is to provide in a nozzle assembly for effecting a finely atomized hollow cone shaped spray stream means affording a swirl chamber of constant size immediately upstream from the spray orifice and wherein substantially constant liquid velocity is maintained throughout a wide range of liquid flow rates in the liquid supply system.

2

A further object of the invention is to provide in a finely atomizing spray nozzle construction improved control means automatically responsive to variations in fluid supply pressures in the course of flow rate variations to control delivery of the fluid to the spray orifice in a manner to maintain constant atomizing efficiency.

Still another object of the invention is to provide novel pressure sensitive control means in a spray nozzle device which operates not only to shut off the nozzle completely in the absence of predetermined minimum fluid pressure, but is also operative throughout a substantial fluid flow rate range to control delivery of the fluid to the spray orifice of the nozzle.

Other objects, features and advantages of the present invention will be readily apparent from the following detailed description of certain preferred embodiments thereof taken in conjunction with the accompanying two sheets of drawings in which:

Figure 1 is a fragmentary longitudinal sectional view, more or less schematic, of a spray nozzle embodying features of the invention;

Figure 2 is a horizontal sectional view taken substantially on line II—II of Figure 1;

Figure 3 is an enlarged fragmentary vertical sectional view through the spray nozzle orifice and swirl chamber immediately upstream therefrom with schematic illustration of the fluid action in developing a predetermined spray pattern;

Figure 4 is a fragmentary vertical sectional view through a modified form of flow control means according to the invention;

Figure 5 is a fragmentary longitudinal sectional view through a further modification;

Figure 6 is a fragmentary longitudinal sectional view through still another modification embodying the features of the invention;

Figure 7 is a longitudinal sectional view through yet another modification;

Figure 8 is a fragmentary longitudinal sectional view through still another modification; and

Figure 9 is a fragmentary longitudinal sectional view through another modification.

As shown on the drawings:

In one form of spray nozzle assembly embodying the features of the invention, a spray nozzle (Figs. 1, 2 and 3) comprises a tubular casing or housing 16 which may serve as an adapter to facilitate mounting of the nozzle and carries a nozzle frame tube 17. At an intermediate portion of the tube 17, it is provided with a radial flange or collar 18 which is threadedly engaged within the end of the casing tube 16 with one portion

of the nozzle frame tube 17 disposed interiorly of the housing tube 16 and the remaining portion of the tube 17 projecting beyond the end of the housing tube. Within the outwardly projecting or forward portion of the nozzle frame tube 17 is a nozzle plug 19 which is fitted in fluid tight relation within the bore of the tube 17.

Within a stepped recess 20 coaxially in the outer end of the plug 19 is mounted an orifice plate or disc 21 having a fixed axial spray orifice 22 therethrough and held removably in place by means such as a retaining ring nut 23 screwed into the outer enlarged portion of the recess 20. Inwardly of the orifice disc 21 and closed by the disc is a cylindrical chamber 24 which is of substantially larger diameter than the orifice 22 and of a predetermined depth. Directed tangentially into the chamber 24 is a series of preferably equidistantly annularly spaced fluid delivery ports 25. Fluid entering the chamber 24 by way of any one or more of the ports 25 under pressure swirls about within the chamber 24 and develops a vortex due to its velocity flowing toward the orifice 22, substantially as indicated at V in Fig. 3. At the orifice 22, the fluid due to its high velocity coaxial whirling motion escapes into the orifice as a thin film of more or less cylindrical tubular shape whirling spirally outwardly along the periphery defined by the orifice and then breaks from the outer rim of the orifice as a whirling finely atomized hollow cone-shaped spray stream identified at S in Figs. 1 and 3. The length or depth of the swirl chamber 24 determines the angle of the spray stream S by determining the length of the vortex V and hence the angle of the vortex which is reflected in the spray stream angle. Since the area and length of the swirl chamber 24 remain fixed, the length of the vortex V remains constant and thus the spray stream S maintains substantially the same cone angle.

According to the present invention means are provided for assuring that the vortex velocity in the swirl chamber 24 will remain substantially constant throughout a substantial range of fluid flow rates in the supply to the nozzle as will occur during operation in accordance with various variable factors such as variations in fluid demand. To this end, each of the delivery ports 25 is preferably of a different cross sectional flow area, graduated in size according to a predetermined range of fluid supply flow rates. A separate fluid supply channel 27 leads to each of the respective delivery ports 25 and may be in the form of a longitudinally extending separate peripheral groove formed in the external periphery of the plug 19. The supply grooves 27 extend short of each opposite end of the plug 19 and are isolated one from the other by the fluid tight interengagement between the periphery of the plug and the embracing wall of the nozzle frame tube 17. Each of the supply duct grooves 27 communicates by way of a communication port 28 in the plug 19 with a cylindrical fuel supply chamber 29 formed as a coaxial bore extending in from the inner end of the plug and terminating short of the swirl chamber 24.

Means are provided for normally maintaining the communication ports 28 blocked against passage of fluid therethrough to the supply ducts 27. Herein such means comprise a piston 30 slidably reciprocable in the cylindrical chamber 29 and of a length to block all of the communication ports 28 simultaneously in one position of the piston, the ports being for this purpose located in an annular area of the wall of the

5 cylindrical chamber 29 corresponding to the length of the piston 30. By preference, the communication ported area is adjacent to the inner or open end of the cylinder 29 so that the forward end of the cylinder affords a substantial clearance for movement of the piston 30 into a position clear of the communication ported area of the cylinder.

10 Means are provided for normally biasing the piston 30 into the communication port closing relation thereof. Herein such means comprise a tension spring 31 connected at one end to a stem 32 extending coaxially rearwardly from the piston 30, the stem being provided with an interlocking end notch 33 for this purpose. The opposite end of the biasing tension spring 31 is hooked onto a cross rod 34 supported by the rear end portion of the nozzle frame tube 17. The spring 31 is of such length and tension that it acts normally to draw the piston 30 rearwardly against an abutment shoulder 35 which may be in the form of a ring shaped member threadedly secured into the rear end of the plug 19 in concentric constricting relation to the rear end or mouth of the cylinder 29. In this position the piston 30 fully closes all of the communication ports 28 and also coacts with the shoulder member 35 to seal the nozzle against leakage of fluid during shutdown.

15 In operation, the biasing spring 31 holds the piston 30 closed until a predetermined fluid supply pressure is exerted against the piston to unseat the piston from the valve seat abutment 35 until at least one of the communication ports 28 is uncovered for passage of the fluid under pressure therethrough and through the associated supply duct 27 to the communicating delivery port 25. By preference all of the communication ports 28 are of the same relatively large size so as to afford relatively unrestricted flow of fluid from supply to the associated port 25. However, the respective communication ports 28 are arranged in progressively spaced relation from the valve seat and abutment shoulder 35 20 in the order of size of the associated delivery ports 25, from the smallest to the largest. That is, the communication port 28 which is connected with the smallest of the delivery ports 25 is disposed, substantially as disclosed in Fig. 1, to be uncovered first in order as pressure develops in the fluid supply. Then as pressure increases the next communication port will be uncovered to supply the next delivery port 25 in order of size, and so on until at maximum fluid pressure all 25 of the communication ports 28 have been opened to admit fluid to all of the delivery ports 25. The cross sectional flow area of each of the radial communication ports 28 and the longitudinal duct or groove passages 27 is large enough in each instance to avoid throttling of the fluid, so that the pressure at the entrance to each of the tangential delivery ports 25 is equal to the pressure in the chamber area upstream from the piston 30 when the respective communication ports 28 are uncovered by forward movement of the plunger or piston 30 under the influence of supply fluid pressure.

30 Since the tangential delivery ports 25 are of progressively larger cross sectional flow area, it will be apparent that while the flow rate of the fluid may increase, the velocity with which the fluid is delivered by the respective delivery ports 25 will remain substantially constant throughout the full range of flow rates in the fuel supply. Consequently, while the volume of fluid in

the vortex V will increase proportionately as the flow rate of the fluid supply increases, its velocity of rotation will remain substantially constant and this will be reflected in substantially constant spray stream cone angle, although the volume of fluid discharged through the orifice 22 will vary proportionately. The diameter of the orifice 22 is such that throughout the entire range of flow rate, it will never fill but always maintain a hollow whirling stream.

At low flow rates it is not only important for good atomization that a sufficiently high pressure drop be maintained at the ports 25, but it is equally important that the flow of fluid be properly directed within the nozzle so that a high rotational velocity is maintained in the swirl chamber 24. Liquid that leaks past the piston 30 will tend to flow into the succeeding radial communication ports 28; from there into the larger tangential delivery ports 25, and thus reach the swirl chamber 24 at low velocity. If this leakage flow is a substantial percentage of the total flow through the nozzle, atomization will be poor. In order substantially to avoid this condition without requiring extremely close fitting of the piston 30 in the cylinder 29, the radial communication openings 28 that feed the smallest tangential delivery ports 25 are located a sufficient distance rearwardly of the next large radial communication ports 28 so that there is a great enough blockage of the path to the communication openings 28 that feed the larger tangential delivery ports 25 to reduce piston leakage to a negligible amount during low flow rates. At higher flow rates, piston leakage is not an important factor. For this reason the radial communication ports 28 that feed the larger tangential delivery ports 25 may be located closer together, and even to the extent that while each port remains independent there may be a slight overlap in uncovering of successive ones by the piston 30.

Pressure relief between the forward end of the piston 30 and the closed end of the cylinder 29 is afforded through a relief port or vent 37 which opens coaxially through the rear of the swirl chamber 24 and due to the hollow core of the rotating fluid in the vortex V and as it passes on through the orifice 22 and in the spray stream S, direct communication with the atmosphere in the space into which the nozzle discharges is effected.

This communication of the forward side of piston 30 with the atmosphere into which the nozzle discharges renders the pressure gradient between the cylinder chamber, forwardly of piston 30, and the atmosphere independent of variations in atmospheric pressure, and hence the pressure drop across the tangentially disposed openings 25 and the velocity of discharge through the openings 25 is made independent of variations in atmospheric pressure.

In Figure 4 is shown an alternative biasing spring arrangement, all other features of the nozzle structure being substantially the same as shown in Figure 1. In this modified form, the piston identified as 30' is provided with a stem 38 carrying at its rear end a retainer flange disc 39 against which the rear end of a coiled compression spring 40 bears while the forward end of the spring bears against the end of the nozzle plug 19. In this arrangement it is practicable to eliminate the inner or rearward extension portion of the nozzle frame tube 17. In this arrangement the spring 40 is of course of such

size and tension that it will normally hold the piston 30' closed in sealing abutment with the shoulder 35 but will yield in response to predetermined fluid pressure to permit forward movement of the piston 30' for uncovering the successive communication ports 28 in proportion to the flow rate of the fuel supply, the spring maintaining the piston 30' in a state of equilibrium in each pressure increment attained as the flow rate varies from time to time in the fluid supply.

In the modification of Figure 5, a nozzle assembly 41 is shown as including a body or adapter tube 42 into the forward end of which is secured a nozzle frame tube 43 which carries fixedly therein a nozzle plug 44. At its forward end the plug 44 is of substantially the same construction as the plug 19 in Fig. 1, including a swirl chamber 45 closed at its forward or open end by an orifice plate 47 providing a spray orifice 48. Leading into the swirl chamber 45 is a series of tangential fluid delivery ports 49 of graduated sizes.

The smallest of the tangential delivery ports 49 communicates with a supply duct groove 50 in the periphery of the plug 44 and to which leads at its rear end a radial communication port 51 which opens through the plug 44 into a cylinder 52 into which fluid is supplied from the supporting tube 42. The communication port 51 is normally closed by a piston 53 which is urged by biasing means such as a coiled compression spring 54 into seating relation with a shoulder 55 with which the piston forms a fluid seal. When the fluid supply pressure reaches a predetermined value the spring 54 is overcome and the piston 53 moves forwardly until it is stopped in fluid sealing relation against a forward shoulder 57 and in which position the communication port 51 is opened to afford a free flow of fluid therethrough and the supply duct 50 to the smallest of the tangential delivery ports 49.

Opening movement of the piston 53 also exposes a port 58 leading to a duct 59 which communicates at its other end through a port 60 with a pressure chamber 61 at the forward end of the cylinder 52. When the pressure of the fluid supply increases sufficiently to overcome the loaded biasing spring 54, a second piston 62 is unseated from a shoulder 63 against which it is normally biased into fluid sealing relation. As the fluid supply pressure increases the piston 62 is moved progressively further from its seat 63 and successively opens a series of individual annularly and axially spaced communication ports 64 by which the fluid is conducted to respective supply ducts 65 for delivery to the respective tangential delivery ports 49 of respectively graduated sizes larger than the minimum size of the delivery port which communicates with the supply duct 50. It will be understood that the arrangement of the delivery ports 49 will be substantially similar to the arrangement shown in Fig. 2 for the delivery ports 25. Communication between the piston chamber and atmosphere is afforded by a relief vent 66 serving the same purpose as the relief vent 37 in Fig. 1. The arrangement of Fig. 5 affords a multiple liquid seal during shutdown and provides certain advantageous features as to fluid control. It is also significant that means is provided whereby leakage past the control piston at low flow rates, during which only the smallest passages 49 are functioning, is entirely eliminated.

The modification of Figure 6 provides a spray

nozzle 67 which is in several respects similar to Figures 1 and 5 in that it affords a conically shaped atomized spray stream of substantially constant size and velocity despite substantial variation in the fluid supply rate. To this end, the nozzle 67 comprises a supporting or adapter tube 68 into the forward end of which is secured a nozzle frame tube 69 carrying a nozzle plug 70 therein similarly as the nozzle plugs 19 and 44 previously described. A swirl chamber 71 of fixed size at the forward end portion of the plug 70 is closed by an orifice plate 72 similarly as in the previously described forms of the invention. One or more supply duct grooves 73 in the periphery of the plug 70 communicate constantly with the supply passage rearwardly of the plug 70 and each of the supply ducts communicates freely by way of a radial port 74 with a fluid supply chamber 75 adjacent to but spaced from the swirl chamber 71. When the fluid pressure reaches a predetermined value, a piston 77 is unseated from a retaining and sealing shoulder 78 at the rear end of the supply chamber 75 and moves rearwardly under the influence of the fluid pressure within a cylinder 79 in which it is slidably contained. A suitable biasing means such as a compression spring 80 normally urges the valve 77 against its sealing seat 78 but is adapted to be overcome by predetermined fluid pressure against the piston 77 so as to open a succession of radial communication ports 81 which lead to respective supply groove ducts 82 in the periphery of the plug 70 to feed a series of respective delivery ports 83 of graduated sizes communicating tangentially with the swirl chamber 71. The relationship and operation of the communication ports 81 and the delivery ports 83 is preferably substantially similar to the operation of the corresponding ports in the forms of the invention shown in Figures 1 and 5. The rear end of the spring 80 is retained by an abutment plug 84 closing the rear end of the cylinder 79. A vent passage 85 to atmosphere communicates with the rear end of the cylinder 79.

In some circumstances it may not be desired to shut off the fluid supply line completely from the orifice during shutdown, and in such event the form of nozzle 15' shown in Figure 7 may be utilized. The construction and arrangement of this nozzle is identical with that in Figure 1 with the exception that the smallest of the tangential delivery ports 25 into the swirl chamber 24 communicates by way of a channel duct 87 directly with the supply passage in the rear portion of the nozzle frame tube 17. The remaining tangential delivery ports 25 are under the control of the spring biased piston valve 30 similarly as in the case of the nozzle 15 of Figure 1. Since the details of structure of the nozzle 15' are substantially identical with those of Figure 1, identical reference numerals designate the same parts.

In the form of the invention shown in Figure 8 a nozzle assembly 15'' is in most respects substantially the same in details of structure as the nozzle assembly 15 of Figure 1. Substantial identity of parts is indicated by use of identical reference numerals to identify such parts. In the nozzle assembly 15'', however, a different form of control valve and piston arrangement is utilized. To this end, a piston 88 is provided for reciprocal sliding engagement within the cylinder 29 for normally closing the radial communication ports 28 in the plug 19 and which

afford communication between the supply ducts 27 and the rear portion of the cylinder 29. The piston 88 is of hollow construction formed with a short threaded stem 89 engaged within a coupling 90 at the forward end of a valve stem extension 91 which is hooked onto the forward end of the tension spring 31. The threaded detachable coupling afforded by the short stem 89 and the coupling 90 enables the assembly about the stem 89, serving as a guide, of a disc valve and pressure plate 92 which is normally urged into separated relation to the rear end of the piston 88 by biasing means such as a coiled compression spring 93. In the normal, fluid pressure free condition of the piston 88 wherein it is biased into port closing relation by the spring 31, the disc valve 92 seats sealingly against a shoulder 94 provided by a retaining and distribution ring 95 threaded into the upper end of the plug 19. In this closed, sealing condition of the valve disc 92, it shuts off from the fluid supply a radial port 97 through the retainer 95 and communicating with an annular forwardly opening distribution groove 98 in the retainer and which in turn communicates with a passage duct 99 feeding the supply duct 27 which in turn feeds the smallest of the tangential delivery ports or the swirl chamber 24. The rear end of the piston 88 is in the fully closed condition of the piston engaged against a stop and sealing shoulder 100 afforded by the inner peripheral margin of the retainer ring 95 which for this purpose slightly overlaps the mouth of the cylinder 29.

When the liquid pressure of the fluid supply rises above a preset value, the auxiliary valve plate 92 is unseated from the shoulder 94 and moves against the bias of the spring 93 until it uncovers the communication port 97 and seats against the rear end of the piston 88. This, of course, starts the spraying action of the nozzle 15''. A continued rise in the fluid pressure acting against the plate 92 causes the plate and piston 88 to move as a unit in opposition to the bias of the spring 31 for successively opening the axially spaced communication ports 28 by which the successively larger delivery ports 25 are fed with fluid in proportion to increase in fluid pressure and thus increased flow rate, operation proceeding as with the nozzle 15 of Figure 1. Any slight leakage past the plate 92 into the hollow piston 88 may drain off by way of a vent opening 101 through the forward face of the piston into the forward vented portion of the cylinder 29.

A nozzle assembly 15''' as shown in the modification of Figure 9, comprises in most respects a similar construction as that disclosed in Fig. 1, as indicated by identification of similar parts by the same reference numerals. In this form, similarly as in the nozzle assembly 15'' of Figure 8, a control valve arrangement is utilized wherein a preliminary or auxiliary valve member is initially motivated by development of pressure in the fluid supply system over a preset value and thereafter the auxiliary member engages with and moves jointly with a principal control member as the flow rate increases. This affords a relatively sensitive fluid pressure responsive control for low flow rate and a more resistant fluid pressure response at higher flow rates. In the valve assembly 15''', an auxiliary fluid pressure responsive piston 102 is movable within a suitable control range between a shoulder 103 and a principal control valve piston 104, the auxiliary piston 102 being normally urged sealingly against shoulder 103 by means such as

a biasing tension spring 105 hooked onto the rear end of a connecting stem 107 on the auxiliary piston. The shoulder 103 is provided by a retaining ring 108 secured into the rear end of a nozzle plug 19' and formed with a forwardly opening annular distribution groove 109 with which communicates a port 110 leading to the cylindrical guide bore for the piston 102 afforded by the retainer 108. The communication port 110 is normally closed by the piston 102 and is adapted to be opened when the piston 102 is urged from its seat 103 by development of pressure above a preset valve in the supply system rearwardly of the piston 102.

Increase in fluid supply pressure acting upon the rear face of the piston 102 drives the same against the rear face of the piston 104 which is slidably reciprocably bearinged in a cylinder 29' in the plug 19' and is normally urged by a preloaded compression spring 111 acting between the piston 104 and the forward blind end of the cylinder 29' against a shoulder 112 afforded by an overlapping inner marginal portion of the retainer ring 108 at the mouth of the cylinder 29'. By preference the rear face of the piston 104 which opposes the piston 102 is formed with a cavity or recessed seat to receive the piston 102 when the latter is forced against the piston 104 by fluid pressure. A vent opening 114 in the head of the piston 104 relieves any pressure that might develop in the operation of the pistons and also drains off any fluid that may possibly leak past the piston 102.

In the operation of the nozzle assembly 15'', after the supply pressure of fluid in the chamber afforded at the rear end of the nozzle frame tube 17 develops to a value greater than that preset by tension of the spring 105, the auxiliary piston 102 is unseated from its sealing and retaining shoulder 103 and opens the communication port 110. This sets the spray function of the nozzle into operation by way of the smallest of the tangential delivery ports 25 into the swirl chamber 24. Upon increase of the fluid pressure to a point where the auxiliary piston 102 seats against the rear face of the principal control piston 104, and further development of pressure to overcome the combined resistance of the springs 105 and 111, the control piston 104 is driven forwardly until the first of the communication ports 28 is opened to increase the volume of fluid sprayed from the nozzle, and this action continues progressively as the fluid supply pressure increases, or decreases in proportion to decrease in fluid supply pressure and return of pistons to closing relation to the successive fluid communication ports 28 and eventually the starting communication port 110.

In any of the forms of the invention shown in Figures 7, 8 and 9, the compression type of control spring as identified at 40 in Fig. 4 may, of course, be utilized by obvious modification.

It will be observed that in the illustrations of Figures 1, 4, 5 and 6, the relationship of the movable parts to the associated parts in the respective nozzle assemblies disclosed is in a state of at least partially open, operative condition. In the forms of Figures 7, 8 and 9, on the other hand, the nozzles are shown in the shutdown condition or at least prior to development of fluid supply pressure greater than the preset value which must be attained before the control valve or piston structure will be unseated for operation.

Where desirable, such well known expedients as elastic gaskets between sealingly cooperative

parts may be utilized in the respective nozzle assemblies. In the more or less schematic illustrations in the drawings, such expedients have been omitted, although in order to make up for slight manufacturing variations or tolerances, such expedients may be desirable in actual practice.

From the foregoing it will be apparent that in all of the various forms of the invention disclosed a wide range of supply fluid flow rates can be accommodated with a substantially constant pressure drop across the nozzle 30 the attainment of this substantially constant pressure drop across the nozzle, excessive pressures are avoided in the fluid supply line to the nozzle orifice at high flow rates but sufficient energy is available at low flow rates for obtaining a fine spray. At any flow rate within the operating range of the nozzle the control valve or plunger of the nozzle assembly is positioned by the interaction of the fluid pressure forces and the spring biasing forces such that equilibrium is reached between them. If the flow rate increases from a predetermined preset value, the state of equilibrium is reached when the valve assembly has shifted to increase the flow area to the swirl chamber to accommodate the increased flow rate. If the flow rate of the supply fluid decreases, the opposite action occurs. By selection of the appropriate nozzle assembly for any particular requirements, optimum efficiency in operation can be secured while nevertheless utilizing the salient principles of the invention.

It may be noted that in all forms of the invention disclosed, the spray orifice is recessed to a substantial depth from the tip of the nozzle housing. The ridge of the recess is set so that a small clearance exists between it and the outlet surface of the spray cone. The spray cone itself is not sharply defined. A fine mist fans out from the surface of the spray cone. This fine mist fills the small clearance between the spray cone and the ridge of the recess, forming a barrier against small particles of carbon that are formed during combustion of the finely atomized fluid. The carbon deposits on the relatively cool surfaces of the nozzle can disrupt the spray if it deposits around the orifice. With the construction shown, carbon may deposit on the ridge at the outside of the recess, but is prevented from depositing in any significant quantity around the orifice, thus assuring extended operation of the nozzle without interference from carbon deposits.

The invention described herein may be manufactured and used by or for the Government of the United States of America for governmental purposes without the payment of any royalties thereon or therefor.

It will, of course, be understood that various details in the present disclosure may be varied through a wide range without departing from the principles of this invention, and it is, therefore, not the purpose to limit the patent granted hereon otherwise than necessitated by the scope of the appended claims.

We claim as our invention:

1. In a method of producing a spray cone of substantially unvarying cone angle, the steps of delivering to a fixed orifice a swirling mass of fluid to be sprayed, deriving said fluid from a supply of variable flow rate, at low flow rate introducing the fluid into said swirling mass in a small stream of substantially a predetermined velocity, and at higher flow rate introducing

11

the fluid into the swirling mass in a larger stream at substantially said predetermined velocity.

2. In a method of producing a spray cone of substantially unvarying cone angle, the steps of delivering to a fixed orifice a swirling mass of fluid to be sprayed, deriving said fluid from a supply of variable flow rate, at low flow rate introducing the fluid into said swirling mass in a small stream of substantially a predetermined velocity, and at progressively higher flow rates introducing additional streams of fluid of proportionately greater volume but at substantially said predetermined velocity into said swirling mass in addition to said small stream.

3. In combination in a spray nozzle assembly of the character described, means defining a fixed spray orifice, means defining a swirl chamber of fixed size immediately upstream from said orifice, said swirl chamber having a plurality of spaced tangentially directed fluid delivery ports opening thereinto, said ports being of respectively different cross sectional flow areas, and means for supplying to said respective ports fluid to be sprayed and of respective flow rates substantially proportioned to the sizes of the respective ports to pass through the ports into the swirl chamber at substantially constant velocity.

4. In combination in a spray nozzle construction for producing a spray stream of substantially conical shape and constant cone angle throughout a substantial range of flow rates of a supply stream of fluid, structure defining a plurality of fluid delivery passages and means for controlling said passages including a control valve mechanism comprising a plurality of spring biased coaxial relatively movable and successively operable members responsive to supply stream fluid pressure over a preset value.

5. In combination in a spray nozzle construction for producing a spray stream of substantially conical shape and constant cone angle throughout a substantial range of flow rates of a supply stream of fluid, structure defining a plurality of fluid delivery passages and means for controlling said passages including a control valve mechanism comprising a plurality of spring biased coaxial relatively movable and successively operable members responsive to supply stream fluid pressure over a present value, said movable members having respective oppositely facing pressure responsive surfaces and having spring means biasing the members to relatively separated positions, but yieldable under fluid pressure thrust against said respective surfaces for relative movement of the members toward one another.

6. In combination in a spray nozzle construction for producing a spray stream of substantially conical shape and constant cone angle throughout a substantial range of flow rates of a supply stream of fluid, structure defining a plurality of fluid delivery passages and means for controlling said passages including a control valve mechanism comprising a plurality of spring biased coaxial relatively movable and successively operable members responsive to supply stream fluid pressure over a preset value, and means for guiding said members for movement in the same direction under the influence of said fluid pressure, said members being operatively interengageable to move jointly in one phase of operation.

7. In combination in a spray nozzle construction of the character described, a nozzle plug

12

having a rearwardly opening cylinder for passage of fluid to be sprayed thereinto, a fluid sensitive control piston operable in said cylinder, a ring retainer mounted at the mouth of said cylinder and partially overlapping said cylinder mouth, spring biasing means normally driving said piston into sealing relation to said retainer, said retainer having fluid passage therethrough, and an auxiliary fluid sealing member normally biased into sealing relation to the retainer passage and responsive to pressure of the fluid supply over a preset value to be moved by the fluid to uncover the retainer passage.

8. In combination in a spray nozzle of the character described, a nozzle frame tube, a nozzle plug in said tube, means at the forward end portion of the plug for effecting a spray stream, means in the rear portion of the plug for controlling fluid supply to said spray means, the plug having a plurality of peripheral longitudinally extending independently isolated passages communicating from the rear portion of the plug with the forward end portion to supply fluid to said spray means, the plug also having a fluid passage in the periphery thereof which opens freely to fluid supply rearwardly of the plug and communicates with the forward portion of the plug.

9. In combination in a spray nozzle construction, a tubular casing, a nozzle frame tube of substantial length and having spaced substantially rearwardly therefrom an externally threaded portion threadedly assembled within the mouth of said tubular casing, a nozzle plug fitted in fluid-tight relation within the bore of the nozzle frame tube, a cylindrical swirl chamber opening forwardly from said plug, an orifice plate closing the mouth of said swirl chamber, said plug having a series of fluid delivery ports opening tangentially thereinto, said plug having fluid passages longitudinally therein communicating with said ports, the rear end of said plug communicating with the interior of said casing tube, and means carried by the plug controlling fluid flow through said passages.

10. In combination in a fuel atomizing nozzle structure adapted for use in supplying atomized fuel into the combustion chamber of a turbo-jet aircraft engine, a tubular nozzle casing, a nozzle plug fitted in said casing and closing the forward end of the casing, said nozzle plug having a cylindrical swirl chamber recessed within the forward end thereof, means in said plug for directing fuel into said swirl chamber, the outer end of the swirl chamber recess being defined by a plurality of stepped counterbores, an orifice plate seated in the innermost of said counterbores, and a threaded retaining ring threaded into the next adjacent outer counterbore and retaining the orifice plate assembled in its counterbore in closing relation to the swirl chamber.

11. In combination in a fuel atomizing nozzle structure adapted for use in supplying atomized fuel into the combustion chamber of a turbo-jet aircraft engine, a tubular nozzle casing, a nozzle plug fitted in said casing and closing the forward end of the casing, said nozzle plug having a cylindrical swirl chamber recessed within the forward end thereof, means in said plug for directing fuel into said swirl chamber, the outer end of the swirl chamber recess being defined by a plurality of stepped counterbores, an orifice plate seated in the innermost of said counterbores, and a threaded retaining ring threaded into the next adjacent outer counterbore and retaining

the orifice plate assembled in its counterbore in closing relation to the swirl chamber, said retaining ring having the outer face thereof flush with the outer end of the plug and the outer end face of the plug and the outer face of the retaining ring affording a substantial radial area about the hollow portion of the ring, said hollow portion of the ring being of greater diameter than the orifice portion of said plate and having a sharp ridge disposed closely adjacent to the perimeter occupied by a conical spray from the orifice to afford a carbon fence against accumulation of carbon about the orifice on the plate.

12. In combination in a conical spray atomizing nozzle, means defining a swirl chamber having an orifice concentrically arranged and a plurality of fluid delivery passages ported into said swirl chamber, and means in control of said passages comprising a bore having adjacent portions of different diameter and pressure responsive pistons respectively slidably operative in said bore portions, certain of said passages being controlled by one of said pistons and the other of said passages being controlled by the other of said pistons, said pistons being exposed to a source of fluid under pressure with the larger piston responsive to lower fluid pressure than the smaller piston by reason of the larger effective pressure area of the larger piston.

13. In combination in a fuel atomizing nozzle, means defining a swirl chamber having a spray orifice therefrom and a plurality of fluid delivery ports leading thereto, said fluid delivery ports having fluid passages communicating therewith and said passages communicating with a bore having adjacent coaxial portions of different diameter, respective pistons of complementary diameter in said bore portions, said pistons being normally biased into separated positions by a common compression biasing spring, the oppositely facing faces of the pistons being exposed to a source of pressure fluid, certain of said passages being controlled by the larger of the pistons and others of the passages being controlled by the smaller of the pistons, the larger piston being shiftable by pressure fluid before the smaller of the pistons for opening the passages controlled by the larger piston by reason of the larger effective area exposed to the pressure fluid by the larger piston.

14. The method of producing a hollow conical atomized spray stream of substantially constant cone angle in the presence of a substantially varying fluid supply flow rate during operation, which comprises delivering the fluid in the form of a vortex of substantially constant angularity to a fixed orifice from which the fluid is to be sprayed as aforesaid, proportioning the volume of the fluid delivered into the vortex in direct proportion to the fluid supply flow rate, and maintaining the velocity of said delivered fluid sub-

stantially constant while effecting said proportioning of the volume of the fluid delivered.

15. In combination in a spray nozzle of the character described, a nozzle frame tube, a nozzle plug in said tube, means at the forward end portion of the plug for effecting a spray stream, means in the rear portion of the plug for controlling fluid supply to said spray means, the plug having a plurality of peripheral longitudinally extending independently isolated passages communicating from the rear portion of the plug with the forward end portion to supply fluid to said spray means, the plug also having a fluid passage in the periphery thereof which opens freely to fluid supply rearwardly of the plug and communicates with the forward portion of the plug, said fluid supply control means in the rear portion of the plug comprising a chamber having a forwardly spring biased control piston movable rearwardly therein, said chamber having in its forward portion and in front of said piston a port communicating with said last-mentioned fluid passage and a plurality of ports in its rear portion controlled by the piston and leading respectively to said plurality of passage.

16. In combination in a spray nozzle of the character described, a nozzle frame tube, a nozzle plug in said tube, means at the forward end portion of the plug for effecting a spray stream, means in the rear portion of the plug for controlling fluid supply to said spray means, the plug having a plurality of peripheral longitudinally extending independently isolated passages under the control of said fluid supply control means and communicating from the rear portion of the plug with the forward end portion to supply fluid to said spray means, the plug also having a fluid passage in the periphery thereof which by-passes said control means and opens freely to fluid supply rearwardly of the plug, said last-mentioned fluid passage having a transverse port at its forward end which communicates directly with said spray means in the forward portion of the plug, independently of said plurality of passages.

HAROLD GOLD.
